UNITED STATES PATENT OFFICE.

CHARLES W. HART, OF CHARLES CITY, IOWA.

CARBURETER.

1,137,135.

Specification of Letters Patent. Patented Apr. 27, 1915.

Application filed March 17, 1908. Serial No. 483,890.

To all whom it may concern:

Be it known that I, CHARLES W. HART, a citizen of the United States, residing at Charles City, county of Floyd, and State of Iowa, have invented new and useful Improvements in Carbureters, of which the following is a specification.

My invention relates to improvements in carbureters.

10 The object of my invention is to provide means for insuring perfect combustion with varying grades of liquid hydro-carbon, by introducing varying quantities of water, or water vapor, which, when delivered in proper proportions, is disassociated in the presence of the carbon, and not only reduces the maximum temperature by latent heat absorption, but increases the pressure in proportion to the steam generated or gases 20 liberated, utilizes the liberated oxygen to aid combustion, and prolongs the high temperature interval by permitting the liberated hydrogen to combine with the carbon.

In the following description, reference is 25 had to the accompanying drawings, in which—

Figure 1 is a plan view of my improved carbureter, partially broken away on the line A—A Fig. 3 to show the by passes. 30 Fig. 2 is a sectional view, drawn on line X—X of Fig. 1, showing one of the float chambers with its valves and the by pass pertaining thereto. Fig. 3 is a sectional view, drawn on line Y—Y of Fig. 1.

35 Like parts are identified by the same reference characters throughout the several views.

Briefly stated, the simplest and I believe, the best means for carrying out my newly 40 invented method consists in subdividing the air in a carbureter, and directing one of the currents into the path of a supply of liquid hydro-carbon to vaporize and atomize the latter, in the desired quantity, another current being at the same time directed into the path of a supply of water to likewise vaporize or atomize the required quantity, and then re-uniting and mixing the two currents, preparatory to the ignition of the 45 mixture in the cylinder of an internal combustion engine, either with or without an additional supply of fresh air which will be admitted to excessively charged mixtures. By subdividing the air currents and mixing 50 each directly with one of the liquids, the

relative proportions of each liquid to the air can be maintained in such a ratio that the quality of the mixture delivered to the engine may be kept substantially at the right proportions by the admission of fresh air 60 through a spring actuated regulating valve, whenever the suction becomes so great as to have a tendency to overcharge the vapor with the liquids or liquid products.

Referring to the drawings, a valve casing 65 1 is provided with a passage 2, controlled and normally closed by a spring actuated valve 3. Air is admitted to the inlet cavity 4 through a duct 5 and the valve 3 being closed, a portion of the air passes to the outlet cavity 6, through a by pass 7, having a port 8 for liquid hydro-carbon, the admission of which is controlled preferably by a needle valve 9. Another portion of the air is delivered from the inlet cavity through a 70 by pass 10, which is provided with a similar water inlet port, controlled, preferably by needle valve 12. The two currents are united and mixed in the outlet cavity 6 and delivered to the engine cylinder through duct 75 13. Whenever the suction is excessive, the valve 3 opens against the tension of spring 14 and delivers an additional quantity of fresh air directly from the inlet to the outlet cavity, thus diluting the charge, which 80 would otherwise contain an excessive supply of liquid in such cases, and also relieving the suction in the by passes.

For light loads, no water is required, and the arrangement is therefore such that it requires a greater degree of suction to draw the water, than to draw the oil. The greater specific gravity of the water alone tends to prevent its delivery when the suction is light, but it will ordinarily be found advisable to 90 95 also maintain the water supply at a somewhat lower level than that of the oil. Water and oil cavities 16 and 17 respectively are preferably provided, and the feed through their inlet ducts 18 and 19 controlled by valves 21 operated by floats 22 to maintain a constant level, with suction ducts 23 leading to the ports 8 and 11 from the oil and water cavities respectively. The valves and floats in the oil cavity are the same as those 100 in the water cavity, the only difference being in the float adjustment. The specific form and arrangement of the several parts of the carbureter, are however, not essential 105 to this invention and the terms and phrases 110

herein employed are used as terms of description and not of limitation, my invention being regarded as of a generic character.

Heretofore attempts have been made to in-

- 5 troduce water vapor or steam into a carbureter for the purpose of facilitating combustion, but I have found that by introducing it in liquid form and causing its evaporation within the cylinder, consider-
- 10 able additional pressure will be developed, and at a lower temperature, since the water will absorb a large number of heat units which become latent with vaporization. The quantity of water introduced can also be
- 15 regulated to suit the requirements of all the varying conditions met in practice, and it is highly essential that means be provided which will adequately maintain the correct proportions of the introduced water to the
- 20 supply of hydro-carbon and air which make up the balance of the charge. By dividing the incoming air and separately charging one portion with water and another portion with hydro-carbon, I am enabled to avoid
- 25 any interference by the vapor absorbed from one of the liquids with the absorption of vapor by the air from the other liquid, and I, therefore, believe that I am the first to

provide for the introduction of water and of hydro-carbon vapor into the air in proper 30 quantity and in the proportions required for the variable charges of explosive mixture delivered to internal combustion engines, since I have not found it practical to introduce both water and hydro-carbon into 35 the same body of air and secure the proper proportions of both by so doing.

Having thus described my invention, what I claim as new, and desire to secure by Letters Patent, is—

A carbureter provided with a mixing chamber, an air inlet, three passages between said inlet and mixing chamber, means for admitting liquid fuel to one of said passages, means for admitting water to another of said passages, and means for resili- 45 ently controlling the passage of a diluting charge of air through the third and central passage.

In testimony whereof I affix my signature in the presence of two witnesses.

CHARLES W. HART.
